X-RAY OF FLOWERS AND THE LIKE

Alice M. McFarland, Cincinnati, Ohio

Application December 28, 1942, Serial No. 470,401

10 Claims. (Cl. 250—65)

This invention relates to a process for producing an artistic picture through the use of the X-ray and novel methods of exposure, development and printing. The process relates particularly to objects of relatively light texture or density such as flowers, fruits and vegetables, and results in reproductions of the forms of such objects together with interior structure which shows in bright contrast with the background produced in accordance with the present invention.

Another object is to produce an X-ray picture of the kind described, in which the background is a solid and unvarying black, whereby striking contrast with the subject reproduced, is achieved.

Another object is to produce the results described in a simple manner requiring only readily available, and for the most part, standard equipment.

These and other objects are attained by the means described herein and shown in the accompanying illustrations, in which Fig. 1 shows a flower reproduced pictorially according to the process of the present invention; Fig. 2 is a vertical cross section of equipment used during the practice of my process and having a flower associated therewith.

While the X-ray has been employed heretofore in pictorially reproducing various kinds of objects, attempts to pictorially represent such objects as flowers, fruits and vegetables, of relatively light texture or density, have not been successful because of the poor background resulting in such pictures, such background having been cloudy and uneven, thus failing to provide a pleasing and proper contrast with the subject of the picture, and likewise producing a generally unattractive total effect.

The present invention overcomes this and other difficulties heretofore encountered in this connection, and makes possible the production of pictures of highly artistic quality.

The process of this invention is practiced as follows, according to a preferred method, it being understood, however, that variations in details of the procedure will readily occur to those skilled in the art. In other words, while the specific process now to be given by way of example, will set forth concrete time elements, distances, etc., the person skilled in the art will find it possible to vary these in proper proportions while maintaining the essentials herein described.

The process is, of course, carried out in a fluoroscopically dark room. A flower, such as the one shown in the illustration is arranged on an uncovered non-screen X-ray film 5, Fig. 2, of such

size as to accommodate the flower. This film is previously positioned in a dark box 6, that is a box with a black interior which will prevent the reflection of light. A suitable cover 7 such as one formed of black paper is placed on the box and the latter is positioned under an open-type X-ray tube suitably supported in a lead glass bowl. The tube may be placed at about 70 inches from the film and thereafter an X-ray exposure is made utilizing low voltage. For example, in a delicate flower such as the one shown in the illustration, 16 to 20 kilovolts are utilized, while for a flower of heavier structure, 20 to 24 kilovolts, 30 milliamperes, may be used. Exposure is made for about 20 seconds. After the X-ray exposure has been made, the X-ray tube is deenergized and brought within a 30 inch distance of the film. The black paper cover is removed from the box, and the flower, still in the same position on the film, is exposed for one second to the light of the filament in the X-ray tube. This has been found a convenient manner of providing a properly positioned light of the quality required for the purpose of the invention. The black interior of the box precludes reflection of light, and the result is that the film, all around the flower is effectively fogged without any areas of lighter background resulting under portions of the flower slightly raised off the film.

30 The film is now transferred, under opaque coverings, to the developing room and developed. It has been found satisfactory to place the film on an X-ray hanger in "Kodak" developing solution at 65° F. for 5 minutes. The film is then removed, rinsed in clear water for 30 seconds and placed in a fixer whereby the emulsion on the film is hardened for further protecting the image. The film is maintained in the fixer for about 15 minutes and is then placed in clear running water for about half an hour. Thereafter the film is properly dried.

45 The negative X-ray so produced is now utilized in making a positive. For this purpose the negative X-ray is taken to the dark room and placed in a printing frame over which an unexposed regular type X-ray film is positioned. A soft light is now produced in the dark room at a distance of about five feet from the two films and on that side of the printing frame wherein the negative X-ray is positioned. The light so produced should be of soft quality and it has been found satisfactory to strike a match and permit the same to burn for approximately 15 seconds. Since X-ray film reacts to light so quickly, it is desirable

to employ the smallest amount possible of light or an over-exposed film will result.

The exposed undeveloped film is then removed from the printing frame, fastened on an X-ray film hanger, placed in "Kodak" developing solution (or the equivalent) at 65° F. for about 3 minutes. The film is then removed, rinsed in clear water for 20 seconds and placed in a fixer for 10 minutes. It is then placed in clear running water for approximately half an hour and thereafter thoroughly dried.

The positive print so produced is now utilized in making the final picture of this invention.

The positive X-ray print is taken to the dark room, and placed in a printing frame along with a sheet of white, semi-mat double weight, photographic paper, such as "N-2 Kodabromide." The two are then exposed to a moderate light for about 5 seconds, with the positive print toward the light, the distance between the film and the light being about 6 feet. An ordinary ceiling light equipped with a 75 watt bulb and covered with a frosted glass bowl has been found satisfactory for this purpose. The exposed sheet of paper is then removed from the frame and placed in the equivalent of the "D-72" photographic developing solution until the image has been developed out to the desired density. The sheet is then removed from the developer, rinsed in clear water for about 20 seconds and placed in a photographic non-acid hypo solution for 20 minutes for fixing the image, after which the sheet is placed in clear running water for about an hour. Thereafter the print is placed between two pieces of smooth white cloth, which in turn are covered by a pair of cardboard sheets, and so permitted to dry.

The resultant picture is as disclosed in the illustration, with the image showing light in varying degrees from the relatively shaded portions of the petal bodies to the pure white of the denser portions, such as the stem, stamens, etc., of the flower. The background is uniformly and completely black and provides an excellent contrast for the white, crystal-like image reproduced.

As already stated, modifications will suggest themselves upon consideration of the means herein disclosed but these are believed to be comprised within the spirit and scope of the invention.

What is claimed is:

1. The process of making an X-ray picture of objects of relatively light texture or density, such as flowers, the process comprising making a negative of the object on a non-screen X-ray film, exposing the undeveloped negative with the object positioned thereon to a flash of light, developing the negative, making a positive from said negative on regular type X-ray film, developing the positive, and making a final negative print from said positive.

2. The process of making an X-ray picture of objects of relatively light texture or density, such as flowers, the process comprising making a negative X-ray exposure of the object, subjecting the exposed film with the object positioned thereon to a flash of light, making a positive from said negative by exposing the juxtaposed films to soft light, and printing the positive so produced on white paper to produce the final picture with background black and the object pictured light.

3. The process of making an X-ray picture of objects of relatively light texture or density, such as flowers, the process comprising making a nega-

tive low voltage X-ray exposure of the object, subjecting the exposed film with the object positioned thereon to a flash of light, developing the negative so produced, making a positive from said negative by exposing the juxtaposed films to a soft light relatively distant from the films, developing the positive so made, printing the positive on a suitable final sheet by exposing the sheet and the positive to a moderate light, and developing said sheet.

4. The process of making an X-ray picture of objects of relatively light texture or density, such as flowers, the process comprising placing such an object on a non-screen X-ray film, making an exposure by use of an X-ray tube positioned above said film, exposing the film with the object positioned thereon to light for a brief interval, developing the film, printing the negative so produced on a regular type X-ray film by use of a small light placed at a substantial distance from the two films and maintained for a short interval, developing the positive so produced, printing the positive on a sheet of white paper by exposing said positive and sheet to a moderate light for a brief period, and developing the exposed sheet.

5. The process of making an X-ray picture of objects of relatively light texture or density, such as flowers, the process comprising making an exposure of such an object placed directly on a non-screen X-ray film in a covered dark box, the X-ray tube being spaced a substantial distance from the film and actuated under low voltage, reducing the distance between the film and the X-ray tube, uncovering the box and momentarily energizing the filament of said tube, developing, fixing and drying the film, printing the negative so produced on a regular type X-ray film by use of a small light placed at a substantial distance from the two films and maintained for a short period, developing, fixing and drying the positive so produced, printing the positive on a sheet of photographic white paper by exposing said positive and sheet to a moderate light, and developing, fixing and drying the exposed sheet.

6. The process of making an X-ray picture of objects of relatively light texture or density, such as flowers, the process comprising making an exposure of such an object placed directly on a non-screen X-ray film positioned in a dark-colored box under a dark cover, the X-ray tube being placed approximately seventy inches above the film and actuated under low voltage for about twenty seconds, reducing the distance between the film and the X-ray tube to about thirty inches, uncovering the box and energizing for about one second the filament of the X-ray tube, developing, fixing and drying the film, placing the negative so produced in close proximity with an unexposed X-ray film in a dark room and printing the former on the latter by lighting a soft light for about fifteen seconds at a distance of about five feet from the films, developing, fixing, and drying the positive so produced, placing the positive in close proximity with a sheet of white photographic paper in a dark room, printing the former on the latter by lighting a shielded light of about seventy-five watt strength at a distance of about six feet for a period of about five seconds, and developing and drying the sheet upon which a print has been so produced.

7. The process of making a negative X-ray exposure of an object and comprising placing the object directly on a suitable film, exposing

the object and film to low-voltage X-rays above 15 kilovolts with a shield such as dark paper interposed between the object and the source of rays, removing the shield, and exposing the object and film to a flash of light.

8. The process of making a negative X-ray exposure of an object and comprising placing the object directly on a suitable film, exposing the object and film to low-voltage X-rays above 15 kilovolts, and thereafter exposing the film with the object still positioned thereon to a brief interval of light.

9. The process of making a negative X-ray exposure of an object and comprising placing the object directly on a suitable film, exposing

the object and film to low-voltage X-rays above 15 kilovolts, and thereafter exposing the film with the object still positioned thereon to a brief interval of light while shielding the same from reflected light.

10. The process of making a negative X-ray exposure of an object and comprising placing the object directly on a suitable film positioned in a dark-walled compartment provided with a removably-covered opening, exposing the object and film to low-voltage X-rays above 15 kilovolts, removing the compartment cover, and exposing the film with the object still positioned thereon to a brief interval of light.
